UNITED STATES PATENT OFFICE.

LOUIS NEES, OF MINNEAPOLIS, MINNESOTA, ASSIGNOR OF ONE-HALF TO ROBERT J. CHENEY, OF MINNEAPOLIS, MINNESOTA.

WINDOW FRAME AND SASHES.

1,270,433.

Specification of Letters Patent. Patented June 25, 1918.

Application filed June 15, 1917. Serial No. 174,849.

To all whom it may concern:

Be it known that I, LOUIS NEES, a citizen of the United States, residing at Minneapolis, in the county of Hennepin and State of Minnesota, have invented certain new and useful Improvements in Window Frames and Sashes; and I do hereby declare the following to be a full, clear, and exact description of the invention, such as will enable others skilled in the art to which it appertains to make and use the same.

My invention relates to improvements in window frames and sashes, and has for its object to provide means to temporarily support vertically movable window sashes for horizontal swinging movement, whereby said sashes may be swung into a room, so that the same may be washed on the outside, painted or repaired.

20 To the above end, the invention consists of the novel devices and combinations of devices hereinafter described and defined in the claims.

In the accompanying drawings, which 25 illustrate the invention, like characters indicate like parts throughout the several views.

Referring to the drawings,

Figure 1 is an inside elevation of a window frame and upper and lower vertical 30 sliding window sashes having the invention incorporated therein, some parts being broken away, other parts being shown in vertical section, and still other parts being shown in different positions by means of 35 broken lines;

Fig. 2 is a vertical section taken on the line 2—2 of Fig. 1;

Fig. 3 is a fragmentary plan view showing the window sashes swung horizontally 40 into the room with some parts sectioned on the line 3—3 of Fig. 1;

Fig. 4 is a view corresponding to Fig. 1, but on a reduced scale and with the window sashes positioned as shown in Fig. 3; and

45 Fig. 5 is a fragmentary inside elevation, with some parts sectioned on the line 5—5 of Fig. 2, on an enlarged scale, and showing the movable section of the window frame adjusted to permit the window sashes to 50 clear the opposite window stops and be swung horizontally.

The numeral 6 indicates a window frame

having inner, outer and intermediate sash stops 7, 8 and 9, respectively, and also having at each side a weight-box 10. An upper 55 window sash 11 and a lower window sash 12 are mounted in the window frame 6 for vertical sliding movement, the former between the outer and intermediate sash stops 8 and 9, and the latter between the inner and intermediate sash stops 7 and 9. Sash cords 13 and weights 14 are provided for counterbalancing the window sashes 11 and 12. The sash cords 13 are secured to the window sashes 11 and 12 in the customary manner, 65 but it is important to note that the sash cords 13, at the right, with respect to Fig. 4, are attached directly to the window frame 6, and the respective weights 14 are provided with pulleys 15, which travel on the intermediate portions of said cord within the respective weight-box 10. The purpose of thus attaching said sash cords 13 to the window frame 6 and connecting the weights thereto is to secure an increase in length of 70 75 said sash cords, for a purpose which will presently appear.

The left hand side member of the window frame 6 is provided with an intermediate section 16, located between the inner and outer stops 7 and 8, respectively, and arranged to be moved horizontally into the adjacent weight-box 10. The ends of the window frame section 16 have beveled engagement with the adjacent portions of the 85 window frame 6 and said bevels are so formed, as to prevent the section 16 from being moved toward the window sashes out of alignment with the outer face of the window frame 6, of which said section forms a 90 part. The intermediate sash stop 9, at the left, with respect to Fig. 1, is made in three sections and the central section thereof extends over the movable section 16 of the window frame 6 and is secured for common 95 movement therewith.

Embracing the sectional sash stop 9 and overlapping the joints therein, are upper and lower channel bars 17 that are rigidly secured to the end member of said sash stop 100 9. Extending transversely through the intermediate web of each channel bar 17, is a screw 18 having in its head an annular groove 19 in which said web extends to hold

the screw against axial movement, but with freedom for rotary movement. On the outer end or head of each screw 18, is secured a crank 20 by which said screw may 5 be rotated. The inner ends of the screws 18 work through apertures 21 formed in the end members of the sectional sash stop 9 and have screw-threaded engagement with a nut-block 22 integrally formed with plates 23, 10 screwed or otherwise secured to the inner face of the window frame section 16. By operating the cranks 20, the window frame section 16 may be moved into the adjacent weight-box 10, as indicated in Fig. 5. 15 When the window frame section 16 is in normal position, the nut-blocks 22 extend into the apertures 21 and the plates 23 overlap the joints formed by the window frame section 16 and assist in rigidly holding said 20 section in position.

Two-part hangers 24, connected by hinge joints, and coöperating hinge lugs 25 are provided for supporting the window sashes 11 and 12 from the movable window frame 25 section 16, with freedom for horizontal swinging movement. The hangers 24 are arranged in a vertically spaced pair for each window sash and set into seats formed in the window frame section 16, so that they 30 are flush with the outer face thereof and do not, in any way, interfere with the vertical sliding movement of said sashes. The lower members of the hangers 24 are rigidly secured to the window frame section 16 by 35 screws and the upper sections thereof are free to be turned horizontally outward and held in this position by the formation of the hinge joints. The movable members of the hangers 24 are reduced in transverse width, 40 so as to clear the sash cords 13 and not interfere therewith. These movable members of the hangers 24 have formed therein longitudinal slots 26, which terminate at their inner ends in lateral extensions 27. The 45 hinge lugs 25 are integrally formed with hinge plates 28, set into the top and bottom rails of the window sashes 11 and 12 and rigidly secured thereto by screws. The outer ends of the hinge lugs 25 are bent 50 laterally and transversely of the window sashes to form hooks.

To connect the window sashes to the hangers 24, the lower sash is first raised and the movable members of the two lower 55 hangers turned horizontally outward and said sashes then lowered thereon. This movement of the window sashes will carry the hinge lugs 25, on their lower rails, into the slots 27 of the lower hangers 24 and the 60 hooked ends of said lugs will pass through the lateral extensions of said slots. The movable sections of the upper hangers 24 are then turned horizontally downward onto the top rails of the window sashes, which 65 brings the upper hinge lugs 25 into the slots

of said upper hangers and the hooked ends of said lugs through the lateral extensions of said slots.

With the window sashes thus supported by the hangers 24, the cranks 20 are operated 70 to move the window frame section 16 into the adjacent weight-box 10 a distance sufficient to permit the free vertical edges of the window sashes to swing horizontally inward by the adjacent sash stops 7 and 9. 75 The sashes are then swung slightly into the room to clear the window frame and the cranks 20 again operated to bring the window frame section 16 back into normal position. The two sashes may be then 80 swung into positions, substantially as shown in Fig. 3. In swinging the sashes into these positions, the hinge lugs 25 thereof work or are forced into the outer extremities of the slots 27 in the movable members of the 85 hangers 24, which carries their hooked ends out of registration with the lateral extensions of said slots, and thereby securely interlocks the hangers 24 and hinge lugs 25.

With the window sashes swung into the 90 room; as described, they may be washed on the outside, painted or repaired, and then returned to their normal positions. With the window sashes in this position, it is also an extremely simple matter to paint the window 95 frame from the inside of the building. The extra long sash cords 13, attached to the free horizontal swinging edges of the window sashes, permit said window sashes to be swung horizontally into a room, without 100 detaching the sash cords 13 therefrom, as shown in Fig. 4.

What I claim is:—

1. The combination with a window frame having vertical inner, outer and intermediate sash stops, upper and lower window sashes mounted between the sash stops for vertical sliding movement, one side of the window frame having a movable section, the respective intermediate sash stop being 105 sectional with the section thereof extending over the movable section of the window frame secured thereto, means detachably connecting the window sashes to the movable section of the window frame for horizontal swinging movement, and means for adjusting the movable section of the window frame horizontally to carry the window sashes into and out of interlocking engagement with opposite sash stops. 110

2. The combination with a window frame having vertical inner, outer and intermediate sash stops, upper and lower window sashes mounted between the sash stops for vertical sliding movement, one side of the window frame having an intermediate movable section between its inner and outer sash stops, the respective intermediate sash stop being sectional with the section thereof extending over the movable section of the 125 130

window frame secured thereto, means detachably connecting the window sash to the movable section of the window frame for horizontal swinging movement, the fixed 5 members of the sectional intermediate sash stop having channel extensions removably holding the movable section thereof, and means carried by said extensions for adjusting the movable section of the window

frame to carry the window sashes into and 10 out of interlocking engagement with opposite sash stops.

In testimony whereof I affix my signature in presence of two witnesses.

LOUIS NEES.
